CLAIM

The ornamental design for a display board as shown and described.

DESCRIPTION

FIG. 1 is a top, front, right isometric view of a display board in accordance with our new design;

FIG. 2 is a top, rear, right isometric view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a top, front, right isometric view of a display board in accordance with our new design;

FIG. 10 is a top, rear, right isometric view thereof;

FIG. 11 is a front view thereof;

FIG. 12 is a rear view thereof;

FIG. 13 is a left view thereof;

FIG. 14 is a right view thereof;

FIG. 15 is a top view thereof; and,

FIG. 16 is a bottom view thereof.

Broken lines shown in the drawings illustrate structure and/or features which form no part of the claimed design. The dash-dot-dash lines in certain figures indicate a boundary line. The break lines of FIGS. 9-12 represent sections of the display board of indeterminate length.
